(57) **CLAIM**

The ornamental design for a backpack with removable fanny pack, as shown and described.

DESCRIPTION

FIG. 1 is a perspective view of a backpack with removable fanny pack showing my new design;

FIG. 2 is a front view thereof;

FIG. 3 is a rear view thereof with the buckle of the fanny pack unbuckled;

FIG. 4 is a side view thereof, the opposite side being a mirror image thereof;

FIG. 5 is another side view from the side of FIG. 4 depicting the beginning of the removal of the strap of the fanny pack from the backpack;

FIG. 6 is a perspective view from the perspective of FIG. 1 depicting a further stage of removal of the fanny pack;

FIG. 7 is a front view thereof depicting yet a further stage of removal of the fanny pack; and,

FIG. 8 depicts the backpack with the fanny pack removed from the backpack.

The shading in the figures represents color contrast. The thin broken lines along various seams depict stitching that is part of the claim. The heavy broken lines depict zippers that are part of the claim. The bottom of the article is not shown in the drawing or described in the specification. The appearance of any part of the article not shown in the drawings or described in the specification forms no part of the claimed design.
